BY *John Minnocks* ATTORNEY

UNITED STATES PATENT OFFICE.

LAYARD CAMPBELL, OF NEW YORK, N. Y., ASSIGNOR TO JOHN W. LESLIE AND JOHN H. LESLIE, BOTH OF CHICAGO, ILLINOIS.

WIRE-STRAPPING TOOL.

Application filed June 22, 1920. Serial No. 390,950.

To all whom it may concern:

Be it known that I, LAYARD CAMPBELL, a citizen of the United States, and a resident of the city of New York, borough of Manhattan, county and State of New York, have invented certain new and useful Improvements in Wire-Strapping Tools, of which the following is a full, clear, and exact description.

- 10 Among the principal objects which the present invention has in view are: to perfect the seal; to more securely fasten the seal formed by the tool; to obviate the necessity for using pliers or other separate tools for 15 cutting the wire after the seal is made; and to shorten the time factor in the operation of making the seal.

Drawings.

- 20 Figure 1 is a side elevation of a tool constructed in accordance with the present invention;

Figure 2 is a top plan view of the same; Figure 3 is a schematic view on reduced 25 scale, indicating the operative positions assumed by the tool at the initiation and completion of the operation of sealing, when using the tool herein disclosed;

Figure 4 is a cross section, on enlarged 30 scale, of the tool, the section being taken as on the line 4—4 in Figure 1 and showing in addition in dotted lines the relative position which the conductor C will occupy when the device is in its inverted position.

- 35 Figure 5 is a side elevation of the device in its inverted position showing how the binder is raised off of the package into a position to be seized by the twisting apparatus.

Description.

40 The wire straps herein mentioned are employed for reinforcing wooden boxes or other packages principally for transportation. The strap generally used is of the so-called 45 bale wire type. This wire has a loop A, preliminarily formed by returning a section of the wire upon itself, and twisting it in position. These wires are delivered in bundles, and approximate in straight lengths 50 the required dimensions.

In practice the wire strap is passed around a carton and the straight end is threaded through the loop A, the wire is drawn taut and the straight or threaded end is then bent 55 back on the loop and is usually clipped or

the surplus wire is cut away and the free end is tucked under the body of the wire adjacent thereto to prevent its being dislocated to draw through the loop. Several machines have been perfected for accomplishing this 60 purpose; one such machine is described and claimed in an application for patent filed by me the 14th day of April, 1920, Serial No. 373,708, on an improvement in wire strapping tools, to which application cross reference is here made. The present tool is, in fact, an improvement upon the tool disclosed in the said application.

In the present tool the point 8 is bifurcated, as in the former tool, in advance of 70 the studs 9. As in the former tool the studs 9 hold the loop A of the strap, while the free end B thereof is being drawn through the loop A, to tighten the strap on the carton or package. The free end is primarily held 75 by a dog 10, which is pivoted on the pin 11 extended from the side of the take-up lever 12. The dog 10 has a serrated end which grips the wire and holds the same against the stud 13 set out from the side of the lever 12. 80

As disclosed in the application referred to, the lever 12 is pivoted by the bolt 14 on the hand bar 15, and the hand bar 15 is twisted as shown in the drawings to form the flattened section 16, at the extremity of 85 which is the bifurcated point 8. Both the lever 12 and the hand bar 15 are provided with laterally extended handles 17, to facilitate the movement imparted to the said members. 90

In the present tool provision is made for twisting the free end B of the strap on the body of the strap adjacent to the loop A, for the purpose of forming a second loop 95 on the so-called free end of the wire. This loop when formed prevents the free end of the wire from loosening or straightening out, so that there is no danger of pulling through the loop A. Also provision is made for severing the free end to rid the same 100 of the surplus material which may result from the use of straps which are of over length. The wires are twisted primarily by means of a slotted gear pinion 18. The pinion 18 has a bearing in a bracket standard 105 19, which is made fast as by the bolt 20 to the flattened section 16 of the bar 15. The flattened section 16 is bored to form a bearing for the beveled gear wheel 21 which is meshed with the pinion 18. A crank 22 is 110

employed for rotating the gear wheel 21, and the pinion 18. To this end the crank is furnished with the handle 23. As shown best in Figure 4 of the drawings, the slot 5 24 in the said pinion extends from the perimeter thereof past the center thereof. The distance to which the said slot is cut past the said center is equal to one and one-half times the diameter of the wire on which the 10 strap is made. As hereinafter explained, the purpose of so forming the slot is to permit the free end of the wire being sheared or severed without endangering the body of the wire around which the free end is then 15 twisted.

The ratio between the pinion 18 and the wheel 21 is such that the pinion 21 is revolved the necessary number of turns to the one complete revolution of the wheel 21, and 20 the relation further provides that when the crank 22 is parallel with the bar 15, the slot 24 is perpendicular to the section 16 with the open end of the slot uppermost. This is the natural position for the crank 22 when 25 the loop A of the strap is primarily placed between the studs 9. As the strap is placed loosely in position on the package before the tool is brought into operation, the free end B is passed through the bifurcation in the 30 point 8. As the free end is placed between the dog 10 and the stud 13 the body of the said free end naturally drops into the slot 24 in the pinion 18, and through the opening provided therefor at the upper edge of 35 the bracket 19. With the wires so disposed, the lever 12 is shifted forward, rocking on the bolt 14 to engage the free end B as far forward as the operation suggests or permits. With the tool then braced against the 40 loop A, and the loop A being held by the studs 9, the lever 12 is drawn back, the dog 10 gripping the wire, so that the full force of the lever is exerted to draw the free end B through the loop A, through the slot in 45 the point 8, and through the slot 24 in the pinion 18, seating the wire firmly in the bottom of the said slot.

When the strap has been drawn sufficiently tight the tool is turned over on the point 50 8, as shown in Figure 5 and also Figure 3 of the drawings, where the full line representation of the tool is the position assumed thereby when the wire has been tightened, and the broken lines in the figure show the 55 position assumed by the tool when overturned upon the point 8 and upon the rockers 25. Upon reversing the position of the tool, the point 8 passes under the loop A and the rockers 25 operate to lift the body 60 of the strap from the package as shown in Figures 3 and 5 of the drawings, and dispose the wire within the slot 24, when the end of the bracket 19 rests on the package.

It will now be observed that the handle 65 23 of the crank 22 is upturned, and in posi-

tion to be easily engaged by the operator, who, holding the lever 12 and bar 15 with one hand in the overturned position, grasps the handle 23, and revolves thereby the wheel 21, and the pinion 18. As the pinion 18 revolves, it picks up the body of the strap and draws the same to the center of the pinion 18, where it continues to remain while the free end B of the wire is being twisted thereabout. During three-quarters of the first revolution of the pinion 18, the free end B is held taut by the dog 10, and the lever 12. During the further rotation of the pinion 18, the wire forming the free end B is severed by the cutter bar 70 75 26, the cutting edge 27 whereof is disposed in the path of the wire forming the free end B, and out of the path of the body wire C of the strap. The cutter bar 26 is a square loop which is rigidly mounted upon the 80 85 bracket 19.

After the surplus material of the free end B has been severed, the pinion 18 continuing to revolve, twists the remainder of the free end B about the body of the wire C, making a substantial and perfect seal, which is not in danger of becoming detached to pull through the loop A.

When the crank 22 has completed a cycle, and assumed its initial position, it will be 95 found that the slot 24 is in position to permit the wire C and free end B twisted about the same to be delivered from the said pinion. The tool is then rocked back to the position shown by full lines in Figure 3 of the 100 drawings, and the studs 9 are drawn backward out of engagement with the loop A, the sealing of the strap having been completed.

As seen bent in Figure 2 of the drawings, 105 the hand bar 15 is offset from the lever 12 by the bracket extension 28. The offset thus formed is provided to allow the passage of the stud 13 and dog 10 when the lever 12 is disposed in juxtaposed parallel relation to 110 the bar 15. While I have found the bar 15 a helpful feature, it is not essential to the complete operation of the tool. In some instances, it is preferred to sever the bar 15 adjacent the bolt 14, and between the said 115 bolt and the offset bracket 28. It is found that the tool may be readily manipulated when using the crank 22 and the lever 12 for this purpose. It is obvious that after the tool has been set to engage the loop A and 120 free end B, the hand bar 15 performs almost no function that cannot as well be performed by the crank 22, to-wit, the over-turning of the tool to the position shown by broken lines in Figure 3 of the drawings. 125

Claims.

1. A tool as characterized comprising a rigid member for holding the looped end of a bale wire; a pulling member for engaging 130

the free end of the bale wire; rotary means for engaging the free end when tightened and the body portion of the wire adjacent said loop for maintaining the parallel relation of the said free end and body within said rotary means, said means embodying a gear pinion having a radially disposed slot therein for holding said free end and body portion of said wire during the rotation of said pinion; and means for severing said free end for eliminating the surplus wire thereof, said means embodying the slot in said pinion and a shearing blade rigidly held in juxtaposed relation to the face of said pinion in the rotary path of the wire forming said free end during the rotation of said pinion.

2. A tool as characterized comprising a rigid member for holding the looped end of a bale wire; a pulling member for engaging

the free end of the bale wire; a rotary means for engaging the free end when tightened and the body portion of the wire adjacent said loop for maintaining the parallel relation of the said free end and body within 25 said rotary means, said means embodying a gear pinion having a radially disposed slot therein for holding said free end and body portion of said wire during the rotation of said pinion; and means for severing said free 30 end for eliminating the surplus wire thereof, said means embodying a slot in said pinion, said slot extending from the periphery of said pinion past the rotary center thereof, a distance greater than the diameter of 35 the said wire, and a cutting implement stationarily disposed in juxtaposed relation to the face of said pinion in the rotary path of said free end when moved by said pinion.

LAYARD CAMPBELL.
